(57) **CLAIM**

The ornamental design for a vehicle console kit, as shown and described.

DESCRIPTION

FIG. 1 is a perspective view of the kit according to my new design in a first configuration;

FIG. 2 is a front view of the kit of FIG. 1;

FIG. 3 is a right side view of the kit of FIG. 1;

FIG. 4 is a rear view of the kit of FIG. 1;

FIG. 5 is a left side view of the kit of FIG. 1;

FIG. 6 is a top view of the kit of FIG. 1;

FIG. 7 is a bottom view of the kit of FIG. 1;

FIG. 8 is a full side cross sectional view through the kit of FIG. 1;

FIG. 9 is a perspective view of the kit according to my new design in a second configuration;

FIG. 10 is a front view of the kit of FIG. 9;

FIG. 11 is a right side view of the kit of FIG. 9;

FIG. 12 is a rear view of the kit of FIG. 9;

FIG. 13 is a left side view of the kit of FIG. 9;

FIG. 14 is a top view of the kit of FIG. 9;

FIG. 15 a bottom view of the kit of FIG. 9; and,

FIG. 16 is a full side cross sectional view through the kit of FIG. 9.
